ILLUMINABLE ROTATABLE DOUBLE-FACED MIRROR

Stanford Pavenick, South Orange, N.J. (½ Aljen Manufacturing Corp., 115 Grand St., New York, N.Y.)

Original design application Feb. 2, 1970, Ser. No. 21,189. Divided and this application Dec. 30, 1970, Ser. No. 26,710

Term of patent 7 years

Int. Cl. D28—03

U.S. Cl. D86—10

FIG. 1

FIG. 2

FIG. 3

FIG. 4

FIG. 5

FIG. 6

FIG. 1 is a front elevational view of an illuminable rotatable double-faced mirror showing my new design; FIG. 2 is a rear elevation thereof;

FIG. 3 is a top plan view thereof;

FIG. 4 is a right side elevational view thereof;

FIG. 5 is a front perspective view thereof in an opened condition; and

FIG. 6 is a rear perspective view thereof in an opened condition.

The reflecting surfaces illustrated in FIGS. 2, 5, and 6 are rotatable about a horizontal axis on the shafts illustrated with one face thereof being plane and the other face being concave.

This is a division of design application Ser. No. 21,189, filed Feb. 2, 1970, and now Pat. No. D. 222,197 issued Oct. 5, 1971.

I claim:

The ornamental design for an illuminable rotatable double-faced mirror, substantially as shown and described.
